SEWARD HOMER CALKINS, OF FLUSHING, NEW YORK, ASSIGNOR TO THE TRAITEL MARBLE COMPANY, OF LONG ISLAND CITY, NEW YORK.

PATTERN AND GUIDE STRIP.

Application filed September 8, 1925. Serial No. 55,125.

This invention relates to means for forming patterns and sections, and for guiding and defining the thickness of the several layers used in making up flooring and other surfaces, finished in terrazzo or other material, and particularly to means for locking together the parts of adjacent sections of a wall or flooring.

Pattern and guide strips have heretofore been provided with openings for the material forming the screed coat or underbed of a flooring to pass into, so as to lock adjacent sections of the underbed together, and at the same time lock the strip into the screed coat or underbed, and prevent vertical displacement of the strip.

In such constructions wings have been formed of the cut away portions of the strip, of a length and area corresponding with that of the openings, and extending outward from the side of the strip and at a right angle thereto.

The angular connection of the wings with the body of the strip prevents the strip from being bent at such portions, making it difficult to use the strip when circular or scroll patterns are desired.

One of the objects of the present invention therefore is to maintain the advantages of comparatively large openings in the strip so as to provide a substantial locking connection between two adjacent sections of a wall or flooring, and at the same time make the strip uniformly flexible throughout its length.

The wings cut out from the body of the strip are placed upon the top of the screed layer, and when so placed, the upper edge of the strip defines the height or level of the upper surface of the finishing layer of the material.

For such purpose, and for the purpose of supporting the strip while the finishing layer is being applied, it has been the practice to make the area of the wings as great as the area of the openings that form the lock connections between two adjacent sections of the material, and a considerable amount of material has been unnecessarily used, which being made of brass amounts to a considerable increase in the cost of making the strip.

This invention has for a further object, therefore, to provide a pattern and guide strip with comparatively large openings at 55 a minimum cost.

A further object of the invention is to provide means for locking entire sections of a wall or flooring together instead of locking together only the underbed of adjacent 60 sections.

In pattern and guide strips heretofore used having openings and wings formed at one margin of the openings, the wings have been formed at the upper margin of the 65 openings and consequently one edge of the strip could be used only as the upper edge and the opposite edge of the strip only as the lower edge.

A further object of the present invention 70 is to provide a pattern and guide strip of the capabilities shown herein that can be used reversibly, with either edge of the strip as the upper or lower edge.

These and other objects of the invention 75 are accomplished by the means herein described, but it is to be understood that changes, variations and modifications may be resorted to without departing from the 80 invention.

In the accompanying drawings which illustrate the invention in its preferred form, and in which similar reference numerals indicate corresponding parts throughout several views,

Figure 1 is a perspective view, partly broken away, showing a pattern and guide strip embodying the invention applied to a section of a terrazzo flooring.

Figure 2 is a perspective view, partly broken away, of a strip embodying the invention detached from a flooring.

Figure 3 is a cross section of the strip shown in Figure 2, embedded in a flooring.

Figure 4 is a perspective view of a strip embodying a modification of the invention, and

Figure 5 is a perspective view of a strip embodying a further modification of the invention.

Many and various difficulties have arisen in connection with the efforts to use pattern and guide strips in terrazzo floors, due largely to the fact that the strips are made

of metal while the material forming the surface layer of the flooring is made of marble broken into small pieces, and held together by cement, and the screed layer is generally 70
5 made of sand and cement.

The strip is inserted into the screed layer while the layer is in a semi-plastic condition, and the top or terrazzo layer is applied to the screed layer and against the strip 75
10 after the screed layer has hardened to some extent, consequently there is a certain amount of shrinkage of said layers away from the strip, causing an uneven contraction of the material forming the screed and 15
15 finishing layers.

Sometimes the screed coat is laid on a foundation made of cinders, sand and cement mixed, or broken stone, laid on the floor arches of a building, or laid in two courses 20
20 as layers on a wooden foundation.

Where plain metal strips were used in the prior art to divide a flooring into sections, serious difficulties resulted, due to the fact that the strips divided the flooring into 25
25 independent sections.

These sections in drying shrink, and fully 90 per cent of the shrinkage takes place within six inches of the outer margins of the independent sections.

That is due to the fact that the upper 95 and edge surfaces dry first, and the outer margins of such a section have the shrinkage of the surface, plus the shrinkage of the edges, and when the shrinkage at the edge of one section is added to the shrinkage at the corresponding and opposite edge of an adjacent section, a crack is produced at the strip representing such double shrinkage, and the strip becomes loose in said 40
40 crack.

One of the objects of the present invention is to prevent such double or compound shrinkage at the edges of said sections by locking both the screed layer and the top 100 or terrazzo layer together, and enable the sections to dry out evenly throughout their area, and hold the strip securely in place 105 without producing a crack at the juncture of strip and the floor sections.

As illustrated in the accompanying drawings, 1 represents a thin flat strip of metal, preferably brass, having preferably a continuous unbroken upper edge 2 and a corresponding unbroken lower edge 3.

The strip is made of flexible material so that it may be bent into circular or other desired form to define sections having various outlines.

In width, the strip is substantially equal 110 to the combined height of the screed layer 4 and the finishing layer 5 of a flooring, and the upper edge of the strip defines the level of the finishing layer.

To that end the strip is pressed into the screed layer while that layer is in a semi-

plastic condition, with the upper portion of the strip extending above the upper surface of the screed layer to a height equal to the desired thickness of the finishing or top 70
70 layer.

In order to set the strip into the screed layer so that its upper edge will define the upper level of the finishing layer, lips or wings 6 are formed in the strip by cutting and pressing outwardly portions thereof on 75
75 a longitudinal line spaced from the upper edge of the strip a distance equal to the desired thickness of the top or finishing layer.

When the strip is pressed into the screed layer the wings 6 rest upon the top surface 80
80 of the screed layer and hold the strip in position while the top, or finishing layer material is being placed upon the screed layer and against the strip.

The wings 6 serve not only as supports 85
85 for the strip while the finishing layer is being applied, but they also serve as anchors that prevent any upward displacement of the strip when the flooring is completed and 90
90 in use.

The wings 6 are preferably provided with upturned ends 7, or other equivalent means, that engage the material of the layer adjacent thereto and aid in holding the material in close contact with the strip and prevent the edges of the sections adjacent to the strip from drying in advance of the material forming the body of a section and forming a crack between the strip and such material. 95

When the material forming the finishing layer is being applied to the screed layer such material is tamped along the sides of the strip, and the wings 6 hold the strip in fixed position while the material itself is 100
100 being tamped adjacent thereto.

In pressing out the wings 6, openings 110
110 8 are made in the strip into which the material forming the flooring enters and aids in locking adjacent sections of a flooring together, but the principal means used for that purpose in the present invention consists of comparatively large openings 9 made in the body of the strip, preferably between the wings 6.

A series of openings 9 is made in the upper 115
115 half of the strip and a corresponding series is made in the lower half, with the upper margins of the openings on one half of the strip substantially in line with the lower margin of the openings on the other half of the strip.

These openings 9 are preferably provided with inclined sides 10, making the outer margin of the openings longer than the inner margin, and the body portion of the wings 6 are preferably arranged on the line of the shorter sides of the openings 9. 120
120

By means of such construction, the strip 125
125 is made reversible, and either edge can be 130
130 used for the upper or lower edge.

By means of such construction moreover, the material forming the screed layer enters the lower openings of the strip and forms a locking connection between adjacent sections of the screed coat, and the material forming the finishing or top layer enters the openings formed in the upper half of the strip when in place, and forms a locking connection between adjacent sections of the finishing coat.

By such means any unequal strains and tensions are avoided in the screed and finishing layers relative to each other, unequal drying out of the edge of a layer of one section relative to the other layer of the same section is avoided, and a crack does not form at the juncture of the strip and flooring material.

The wings 6 are made of a width sufficient to support the strip in the screed layer while the finishing layer is being applied and at the same time do not interfere with the flexibility of the strip, but on the contrary enable the strip to be readily and uniformly bent to define any pattern or outline desired.

By forming the openings 9 of comparatively large area, and the wings of only sufficient area to perform their function, and independent of the large openings, a considerable saving is obtained in the cost of construction.

The scrap brass cut out from a strip to form the openings 9, pays for the entire cost of the labor of transforming the original strip into the finished form shown herein.

While for most purposes I prefer to form the wings 6 independently of the openings 9, such construction may be modified in some instances to advantage by making the wings in conjunction with the large opening formed in the strip as shown in Figure 4, wherein wings 11 are formed at opposite ends of openings 12, thereby combining the opening in the strip formed by cutting the wings 11 and the intermediate portion of the openings 12.

These openings 12, like the openings 9, are preferably formed with their outer longitudinal margins longer than their corresponding inner margins, and they are likewise formed on both sides of the central longitudinal line of the strip to lock together adjacent sections of both the screed coat and finishing layers.

In such construction, however, the wings 11 are preferably formed with their lateral edges diverging from the line of their juncture with the body of the strip so that when in place between the screed layer and the finishing layer, they will form a wedge shape lock with said material, and securely hold the adjacent section of the flooring in place and prevent it from drying out and

contracting from the side of the strip and forming a crack at the juncture of strip and section adjacent thereto.

When the device is in use the wings 6 and 11 act as anchors to prevent any upward displacement of the strip and the portions of the strip at the lower margins of the openings 9 and 12 aid materially in so doing.

While I have shown upturned ends 7 formed on the wings 6 to aid in preventing any withdrawal of the flooring material away from the strip, other means having similar capabilities may be employed in connection with said wings, without departing from the invention.

In some instances the wings 13 may be provided with lateral recesses 14 as shown in Figure 5, to engage the material adjacent the strip and aid in preventing the material from shrinking away therefrom.

While for most purposes I prefer to make the strip of metal, and preferably of brass, I do not desire to be limited thereto, other material having satisfactory capabilities may be used instead if desired.

What I claim as new and desire to secure by Letters Patent is:

1. For use as a pattern and guide in laying flooring and other surfaces, finished in terrazzo or similar material, a flat strip of flexible material having uninterrupted straight upper and lower edges, a series of longitudinally disposed openings of greater length than width, extending in width from the central longitudinal line of the strip upward, and a series of openings of greater length than width extending in width from the central longitudinal line of the strip downward.

2. For use as a pattern and guide in laying flooring and other surfaces, finished in terrazzo or similar material, a flat strip of flexible material having uninterrupted straight upper and lower edges, a series of longitudinally disposed openings of greater length than width extending in width from the central longitudinal line of said strip upward, and a series of longitudinally disposed openings of greater length than width, extending in width from the central longitudinal line of the strip downward, arranged in staggered relation to the openings on the upper half of said strip.

3. For use as a pattern and guide in laying flooring and other surfaces finished in terrazzo or similar material, a flat strip of flexible material having a series of longitudinally disposed openings on the upper half and on the lower half of said strip respectively, and a series of wings formed in said strip at substantially the central longitudinal line thereof, in line with the inner margins of the upper and lower series of openings.

4. For use as a pattern and guide in lay-

- ing flooring and other surfaces finished in terrazzo or similar material, a flat strip of flexible material having a series of longitudinally disposed openings on the upper 5 half and on the lower half of said strip respectively, with the inner margins of both series of openings in line with each other, and wings forward in said strip at the opposite ends of said openings.
- 10 5. For use as a pattern and guide in laying flooring and other surfaces finished in terrazzo or similar material, a flat strip of flexible material having a plurality of openings of greater length than width, extending 15 in width from the central longitudinal line of the strip upward and wings adjacent each end of said openings formed on said central longitudinal line, and a plurality of openings of greater length than width, extending in width from the central longitudinal line of the strip downward, with wings adjacent the ends of said openings formed on said central longitudinal line of said strip.
- 20 6. For use as a pattern and guide in laying flooring and other surfaces finished in terrazzo or similar material, a flat strip of flexible material having a plurality of openings of greater length than width, and provided with inclined ends, said openings extending 25 in width from the central longitudinal line of the strip upward, and wings adjacent the ends of said openings formed on said central longitudinal line, and a plurality of openings of greater length than width extending 30 in width from the central longitudinal line of the strip downward and provided with inclined ends and wings adjacent the ends of said openings extending 35 from the central line of said strip.
- 40 7. For use as a pattern and guide in laying flooring and other surfaces finished in terrazzo or similar material, a flat strip of flexible material having a plurality of openings of greater length than width, extending 45 in width from the central longitudinal line of the strip upward, and a plurality of openings of greater length than width, extending in width from said longitudinal line downward, and wings arranged at the ends 50 of said openings extending from said central longitudinal line and provided with means for locking said wings into the material of a wall or flooring.
8. For use as a pattern and guide in laying flooring and other surfaces finished in terrazzo or similar material, a flat strip of flexible material having a plurality of openings of greater length than width, extending 55 in width from the central longitudinal line of the strip upward, and a plurality of openings of greater length than width, extending in width from said longitudinal line downward, and wings arranged at the ends 60 of said openings and provided with edges 65 diverging from their connection with said strip outwardly.
9. For use as a pattern and guide in laying flooring and other surfaces finished in terrazzo or similar material, a flat strip of flexible material having an uninterrupted straight upper edge, a series of longitudinally disposed openings on the upper half and on the lower half of said strip respectively, and a series of wings extending 70 along the central longitudinal line of said strip and provided with ends offset from the body of said wings.

SEWARD HOMER CALKINS.
